COMBINED TOOTHBRUSH AND DENTIFRICE TUBE HOLDER

George Buzard, 128 4th St., Marion, Mich. 49665

Filed Oct. 25, 1965, Ser. No. 87,937

Term of patent 14 years

(Cl. D4—3)

FIG. 1.

FIG. 2.

FIG. 5.

FIG. 4.

FIG. 6.

FIG. 1 is a perspective view of a combined toothbrush and dentifrice tube holder;

FIG. 2 is a front elevational view thereof;

FIG. 3 is a top plan view thereof;

FIG. 4 is a bottom plan view thereof;

FIG. 5 is a side elevational view thereof; and

FIG. 6 is a cross-sectional view on line 6—6 of FIG. 3 showing in broken lines and for illustrative purposes only a toothbrush and inverted toothpaste tube.

I claim:

The ornamental design for a combined toothbrush and dentifrice tube holder, as shown and described.
